W. J. MYATT,
REFILLABLE PENCIL HOLDER,
APPLICATION FILED AUG. 3, 1921.

1,420,938.

Patented June 27, 1922.

Inventor
W. J. Myatt,
By Marks of Clerk
Attest.

UNITED STATES PATENT OFFICE.

WILLIAM JAMES MYATT, OF BIRMINGHAM, ENGLAND, ASSIGNOR TO W. J. MYATT & COMPANY LIMITED, OF BIRMINGHAM, ENGLAND.

REFILLABLE PENCIL HOLDER.

1,420,938.

Specification of Letters Patent. Patented June 27, 1922.

Application filed August 3, 1921. Serial No. 489,554.

To all whom it may concern:

Be it known that I, WILLIAM JAMES MYATT, a subject of the King of Great Britain and Ireland, residing at Argent Works, 5 Frederick Street, in the city of Birmingham, England, have invented certain new and useful Improvements Relating to Refillable Pencil Holders (for which I have made application in Great Britain Oct. 4, 10 1920), of which the following is a specification.

This invention has for its object to provide an improved refillable pencil holder.

Referring to the accompanying sheet of 15 explanatory drawings:—

Figure 1 is a side elevation, and Figure 2 a longitudinal section of a pencil holder constructed in accordance with this invention.

20 Figures 3 and 4 are respectively elevations of the two main parts of the feeding device.

In carrying the invention into effect, a tubular body *a* has screwed to one end of it 25 a removable part *b* serving as a guide and support for the lead. The body is slotted (as indicated by *c*) to an extent determined by the total feeding movement required for the lead, and internally is fitted with a pair 30 of relatively movable members *d*, *e* forming the main portions of the lead feeding mechanism. Both members are of cylindrical form, and a part of one slides over a part of the other. Around the one (*e*) 35 and bearing against the other (*d*) is a spiral spring *f* which tends to force the said members apart. The relative movement of these members is limited by a slot or hole *g* in one (*d*) which is engaged by a transverse 40 pin *h* in the other (*e*). The amount of this movement is that by which the lead can be fed forward at each operation of the feeding device. One of the said members (*d*) is adapted to fit tightly against, though it 45 can slide within the interior of the body, and this member is secured to an outer sleeve *i* by a pin *j* which passes transversely through the long slot *c* in the body. The required frictional grip between the member 50 *d* and the body is obtained by a bent steel wire *k* whose sides press by their spring action tightly against the inner surface of the body. This wire is inserted through a transverse hole *k'* in the part *d*. The member *e* is provided with a wire stem *m* which

passes through a guide *n* at the lower end of the body and abuts against the inner end of the lead *l*.

The end of the body opposite that at which the lead projects may contain a receptacle *o* for spare leads.

Starting with a new lead inserted in position, the point of the pencil is pressed against a table, thus pushing the lead inwards until its end is flush with the outer 65 end of the pencil. The outer sleeve *i* is then pressed down along the body to the extent permitted by the relative movement allowed between the members *d*, *e*, of the feeding device. In this action the spring *f* is compressed. On raising the pencil the said 70 spring asserts itself and presses forward the lead through the medium of the wire stem *m* and the second member *e* of the feeding device, the member *d* being meanwhile held 75 stationary by its frictional grip on the body *a*. When it is again required to feed forward the lead the same operation is performed. The feeding movements can be 80 continued until the whole of the lead has been expended. The amount of unexpended lead in the pencil is always apparent by the 85 position of the sleeve *i* on the body. Before recharging, the sleeve is returned to its initial position, and thereby caused to return 90 the feeding device.

Having thus described my invention what I claim as new and desire to secure by Letters Patent is:—

1. In refillable pencil holders, the combination of a slotted tubular body, a sleeve movable on the exterior of the body, a lead carried by the body, a pair of relatively movable feed members within the body, one member being connected to the sleeve and 95 the other adapted to act on the lead, a spring for exerting a frictional grip between the one member and the interior of the body, and a spring acting between the two members, substantially as described. 100

2. In refillable pencil holders, the combination of a slotted tubular body, a sleeve movable on the exterior of the body, a lead carried by the body, a pair of relatively movable telescopic feed members within the 105 body, a pin passing through the slotted body and connecting one of the said members to the sleeve, a bent wire spring attached to the said member and adapted to exert a frictional grip on the interior of the body, a 110

wire stem connected to the other member and adapted to transmit feeding movements to the lead, a peg on the second member engaging an aperture in the first for limiting the relative movements of the two members, a spiral spring around the second member and pressing in an endwise direction on both

members, and a guide for the lead detachably secured to one end of the body, substantially as described.

In testimony whereof I have signed my name to this specification.

WILLIAM JAMES MYATT.
